DESIGN FOR A SHELF OR THE LIKE

Charles Earl Wilkinson, Mason City, Iowa

Application August 3, 1942, Serial No. 107,809

Term of patent 7 years

To all whom it may concern:

Be it known that I, Charles Earl Wilkinson, a citizen of the United States and a resident of Mason City, in the county of Cerro Gordo and State of Iowa, have invented a new, original, and ornamental Design for a Shelf or the like, of which the following is a specification, reference being had to the accompanying drawing, forming a part thereof.

I claim:

The ornamental design for a shelf or the like, substantially as shown.

CHARLES EARL WILKINSON,
